(57) **CLAIM**

The ornamental design for a portion of a computer input device, as shown and described.

DESCRIPTION

FIG. 1 is a left-front perspective view of portion of a computer input device showing my new design;

FIG. 2 is a left-side elevational view thereof;

FIG. 3 is a front elevational view thereof;

FIG. 4 is a rear elevational view thereof;

FIG. 5 is a top plan view thereof; and,

FIG. 6 is a right-front perspective view of an alternative and mirror image embodiment of a portion of a computer input device showing my new design.

The broken line showing of the remainder of the computer input device is for illustrative purposes only and forms no part of the claimed design.
